CEMENT SOLE ATTACHING APPARATUS

Malcolm Seymour, Boston, Mass., assignor to
United Shoe Machinery Corporation, Flemington, N. J., a corporation of New Jersey

Application May 15, 1946, Serial No. 669,854

18 Claims. (Cl. 12—37)

1

This invention relates to apparatus for cement attaching soles to shoes. Heretofore attempts have been made to utilize atmospheric pressure for attaching soles. In these attempts, however, the pressure obtained was inadequate because atmospheric pressure does not generally exceed 14.7 p.s.i.

Objects of this invention are to provide apparatus whereby adequate pressure may be applied to shoes by utilizing atmospheric pressure.

As illustrated, a cylinder, the ends of which have air-tight enclosures is provided and in the cylinder is a rigid piston. By exhausting air from one end of the cylinder while that end is closed and the other end open, the piston is moved by atmospheric pressure toward the closed end. This movement is used to press a shoe and sole together. In the illustrated form, a shoe is rigidly supported by means connected to the cylinder, and a pressure-applying pad is carried by the piston. The ratio of the diameter of the piston to the length of the shoe may conveniently be 2 to 1. The area of the bottom of a medium sized man's shoe is approximately 25 square inches, and the shoe is about 10 inches long. Therefore, with a piston 20 inches in diameter, which has an area of 314 square inches, a pressure of as much as 4,396 pounds may be produced by a nearly complete vacuum. This arrangement would give about 175 pounds' pressure per square inch on the shoe and, since only 75 to 100 p.s.i. on a shoe is required, it will be seen that if only about half the air is exhausted sufficient pressure will be applied to the shoe.

The illustrated apparatus is so arranged that the piston moves in one direction with respect to the cylinder to apply pressure to one shoe and in the other direction to apply pressure to another shoe, the cylinder being arranged to turn about an axis perpendicular to its lengthwise dimension for convenience in placing the shoe in the cylinder and removing it therefrom.

Abutments are provided for yieldingly pressing the shoe upon its pad, prior to movement of the cylinder, to hold it in place on the pad when the cylinder is turned end for end. When the piston moves toward the shoe, this yield is taken up and the piston applies pressure to the shoe through yielding abutments.

These and other features of the invention will appear more fully from the following description when read in connection with the accompanying drawings and will be pointed out in the appended claims.

In the drawings,

2

Fig. 1 is a side elevation of the apparatus partly in vertical section;

Fig. 2 is an elevation of a disk shown in Fig. 1 taken on the line II—II looking in the direction of the arrows; and

Fig. 3 is an elevation of another disk taken on the line III—III of Fig. 1 looking in the direction of the arrows.

In Fig. 1, the numeral 10 indicates a cylinder which is mounted to turn on a horizontal axis at right angles to the longitudinal axis of the cylinder, there being trunnions 12 and 14 on opposite sides thereof which are rotatably mounted in a frame 16 supported on a base 18. The cylinder may be held against movement with either end up by a spring-pressed locking pin 20 arranged to slide longitudinally in the frame 16 and to engage either of two recesses 22 or 24 in the wall of the cylinder. To rotate the cylinder, the locking pin 20 is withdrawn from its recess 22 by its handle 23 and the cylinder rotated 180 degrees until the recess 24 engages the pin 20.

The cylinder has a cover 30 at each end, each cover when open assuming the position shown at the top of Fig. 1 and when closed the position shown at the bottom of the figure. Any suitable means may be provided for hinging the covers and holding them in closed position. As illustrated, each cover has a pair of ears 32 which are connected by a pin 34 to a link 36, the link having a slot 38 to receive the pin. The link is pivoted at 40 to ears 42 on the cylinder. When the cover is open, the link 36 rests on an upstanding portion 44 of the frame 16, the pin 34 then engaging the inner end of the slot 38 and a lug 46 on the cover engaging the link 36 to prevent further opening movement of the cover.

Each end of the cylinder has a flange 48 in which is a groove 50 to receive a bead 52 on a gasket 54 of suitable yielding material such as rubber and each cover has a groove 56 to engage the bead 52 on the gasket. When either of the covers is closed, it is held clamped against the end of the cylinder by a bolt 58 pivoted at 60 to the cylinder 10 so that it can swing into open slots 62 and 64 formed respectively in a flange 48 on the cylinder and in the margin of the cover. The cover is held against the gasket by turning a hand-wheel 66 one of which is provided on each of the bolts 58. Each cover will normally be held by atmospheric pressure against the gasket when closed so that the bolts merely serve to hold the cover in place until a vacuum in that end of the cylinder is initiated.

55 Arranged to slide in the cylinder 10 is a rigid

piston 70 and on each side of the piston is fixedly mounted a pad box 72 in which is a yielding pad 74 held in place by a retaining rim 75. The pad box and pad may be of any desired construction. Preferably, as indicated diagrammatically in the drawing, they are similar to that disclosed in Letters Patent of the United States No. 2,205,400, granted June 25, 1940, upon application of Sidney J. Finn.

Means is provided to hold the shoe yieldingly against the pad prior to movement of the pad against the shoe and then to sustain the shoe toward the shoe and then to sustain the shoe unyieldingly. In each end portion of the cylinder are a toe abutment 76 and a last abutment 77, each of which has the construction shown in section in connection with the toe abutment 76 in the lower end of the cylinder (Fig. 1). In each case the abutment is drilled to receive one end portion of a shaft 78 the other end portion of which is threaded through a curved bracket 80 and carries a hand-wheel 82. Each bracket 80 is mounted to swing on a pin 84 fixed in ears 86 secured to the side walls of the cylinder, the pin extending parallel to the longitudinal axis of the cylinder. The inner end portion of each shaft 78 is reduced in diameter to form a button 88 and a shoulder 90 between which is a pin 92 fixed in the abutment 76. On the shaft 78 between the abutment 76 and the bracket 80 is a compression spring 94 which normally holds the button 88 against the pin 92 and permits the abutment to yield against the spring 94 to a limited extent. To prevent turning of the abutment, a plate or leaf spring 96 is secured to each abutment with its free end resting against a flat face on the bracket 80.

Means is provided to connect with the atmosphere the end portion of the cylinder which may be uppermost and to exhaust the lower portion. For this purpose two air ducts 102 and 104 are provided, one leading from each end portion of the cylinder to the trunnion 14 fixed to the cylinder, the ducts extending longitudinally through the trunnion. A circular plate or disk 106 is mounted on the rear end of the trunnion 14 and fixed against rotation thereon by a pin 107 which is held in place by the head of a screw 108, the screw holding the disk on the trunnion. The duct 102 leads through the trunnion 14 to the plate 106, where it connects with a radial groove 110 (Fig. 2) in the rear face of the plate. The groove 110 leads into a semicircular groove 112 which extends about the periphery of the plate 106 for nearly but not quite a semicircumference. The duct 104 leads in a similar manner to a radial groove 114 communicating with a semicircular groove 115 similar to the groove 112.

Facing the disk 106 is a disk 116 (Fig. 3) having a stem 118 mounted to slide longitudinally in a bearing 120 (Fig. 1) formed in an extension 122 of the frame 16. A key 124 is provided to prevent rotation of the stem 118, and on the stem between the plate 116 and the bearing 120 is a compression spring 126 which holds the plate 116 in frictional, air-tight engagement with the plate 106. The plate 116 has two diametrically opposite ports 128, 130, the port 128 being open to the atmosphere and the port 130 being connected by a pipe 132 to an air pump 134 which will exhaust air from the lower end of the cylinder, while the upper end is connected to the atmosphere through the port 128. With this arrangement, air is exhausted only from the end of the cylinder which is down, the upper end being always connected to the atmosphere through the

port 128. Also, there will be sufficient friction of the piston in the cylinder to prevent its moving unless the air pressure is greater on one side than on the other. Moreover, exhausting the lower end of the cylinder will move the piston only until the piston covers the opening of the duct 102 or to the duct 104 if that is down.

In use, a shoe S with a sole O spotted thereon is placed on the pad 74. The abutments 76 and 77 are swung respectively about their pivots 84 over the last L and the forepart of the shoe, and the hand-wheels 82 are turned until the abutments engage the work and the springs 94 are compressed enough to hold the shoe firmly upon the pad. The cover 30 is then swung into closed position and secured in place by the swinging bolt 58. The bolt 20 is released and the cylinder turned end for end on its trunnions until the bolt 20 engages the recess 24 in the cylinder. Early in this movement of the cylinder the duct 104 is connected with the groove 112 leading to the pipe 132 which is connected to the pump 134 so that, while the cylinder is turning, it is being exhausted and at the same time the duct 102 from the lower end of the cylinder is connected to the groove 115 leading to the port 128 through which atmospheric pressure is restored in that end of the cylinder in which there was a partial vacuum simultaneously with the exhaustion of the other end by the pump 134.

Connected to the trunnion 12 is a sandglass 136 which will be turned over when the cylinder is shifted end for end and will indicate, when provided with the proper amount of sand, the minimum time during which the shoe should remain under pressure.

Having thus described my invention, what I claim as new and desire to secure by Letters Patent of the United States is:

1. Apparatus for cement-attaching soles to shoes comprising a cylinder, a piston, a pad mounted on the piston, abutments carried by the cylinder wall, yielding means between the abutments and the cylinder wall, means for moving the abutments to apply pressure yieldingly to the shoe, means for limiting the yielding movement of the abutments to sustain the shoe positively, and means for moving the pad toward the abutments.

2. Apparatus for cement-attaching soles to shoes comprising a cylinder, a piston in the cylinder, means carried by the cylinder for supporting a shoe having a sole thereon in the cylinder, a pad on the piston to press the sole on the shoe, an air-tight closure for an end of the cylinder, and means for exhausting air from the closed end of the cylinder whereby the piston is operated by atmospheric pressure to move the pad relatively to the shoe support to apply pressure to the shoe.

3. Apparatus for cement-attaching soles to shoes comprising a cylinder, a piston in the cylinder, means for supporting a shoe having a sole thereon in the cylinder, a pad to press the sole on the shoe, an air-tight closure for an end of the cylinder, and means for exhausting air from the closed end of the cylinder whereby the piston is operated by atmospheric pressure to move relatively the shoe support and pad to apply pressure to the shoe.

4. Apparatus for cement-attaching soles to shoes comprising a cylinder arranged to rotate on a horizontal axis so that either end may be uppermost, a piston in the cylinder, a pad fixed to each side of the piston, means for holding a shoe

against movement axially of the cylinder in each end portion of the cylinder, an air-tight closure for each end of the cylinder, and means for withdrawing air from the lowermost end of the cylinder and supplying air to its uppermost end whereby atmospheric pressure causes the piston to move the pad toward the shoe supported in the lowermost end of the cylinder.

5. Apparatus for cement-attaching soles to shoes comprising a cylinder containing a rigid piston, abutments for a shoe and a sole-pressing pad to receive the sole of the shoe, said abutments and pad being so arranged that movement of the piston will relatively move the pad and abutments to apply pressure to the shoe, a cover for closing the end of the cylinder, an air duct leading from the cylinder, and an air pump connected to said duct to exhaust air from the cylinder, said duct entering the cylinder at a point which will be covered by the piston before excessive movement of the piston takes place.

6. Apparatus for cement-attaching soles to shoes comprising a cylinder mounted to revolve on a horizontal axis so that either end may be disposed upwardly, a piston in the cylinder, a pad and a shoe support in each end of the cylinder so arranged that movement of the piston will apply pressure to one shoe and relieve pressure on another shoe, closures for each end of the cylinder, and means for exhausting air from the lower end of the cylinder to cause pressure to be applied to the shoe in that end of the cylinder and to relieve pressure on the shoe in the upper end thereof.

7. Apparatus for cement-attaching soles to shoes comprising a cylinder open at both ends, trunnions on the cylinder at right angles to its longitudinal axis, supports for the trunnions to permit rotation of the cylinder to position either end uppermost, a piston in the cylinder, a closure for each end of the cylinder, means for admitting air to the upper end of the cylinder, means for exhausting air from the lower end of the cylinder to cause downward movement of the piston by atmospheric pressure, and means for causing such movement of the piston to apply pressure to a shoe and sole.

8. Apparatus for cement-attaching soles to shoes comprising a cylinder open at both ends, trunnions on the cylinder at right angles to its longitudinal axis, supports for the trunnions to permit rotation of the cylinder to position either end uppermost, a piston in the cylinder, sole-pressing pads on each side of the piston, means in each end of the cylinder to support a shoe against pressure of the pad, closures for each end of the cylinder, means for admitting air to the end of the cylinder which may be uppermost, and means for exhausting air from the end of the cylinder which may be lowermost to cause downward movement of the piston by atmospheric pressure, thereby pressing the pad upon the shoe in the lowermost end of the cylinder.

9. Apparatus for cement-attaching soles to shoes comprising a cylinder arranged to rotate on a horizontal axis, a piston in the cylinder, a pad fixed to each side of the piston, means for holding a shoe against movement axially of the cylinder in each end portion thereof, an air-tight closure for each end of the cylinder, and means for withdrawing air from the lower end of the cylinder and supplying air to its upper end whereby atmospheric pressure causes the piston to move the pad toward the shoe supported in the lower end of the cylinder, said means being operated

similarly irrespective of which end of the cylinder is lower.

10. Apparatus for cement-attaching soles to shoes comprising a cylinder, a rigid piston in the cylinder, abutments for the shoe carried by the cylinder in each end thereof, a sole-pressing pad on each side of the piston, said abutments and pads being so arranged that movement of the piston will move one of the pads toward a shoe in one end of the cylinder and away from the shoe in the other end of the cylinder, air ducts leading from the cylinder at each side of the piston at points beyond the normal travel of the piston, an air pump to exhaust air from the cylinder, and means for connecting the ducts in turn with said air pump, excessive movement of the piston causing the duct through which air is being exhausted to be cut off from the air pump.

11. Apparatus for cement-attaching soles to shoes comprising a cylinder mounted to revolve on a horizontal axis so that either end may be disposed upwardly, a piston in the cylinder, a pad and a shoe support in each end of the cylinder so arranged that movement of the piston will apply pressure to one shoe and relieve pressure on another, closures for each end of the cylinder, and means for exhausting the air from the lower end of the cylinder to cause pressure to be applied to the shoe in that end of the cylinder and to relieve pressure on the shoe in the upper end thereof, said means beginning to act as soon as the cylinder leaves an upright position and continuing to act after the cylinder assumes an upright position with the ends reversed.

12. Apparatus for cement-attaching soles to shoes comprising a cylinder open at both ends, trunnions on the cylinder at right angles to its longitudinal axis, supports for the trunnions to permit rotation of the cylinder to position either end up, a piston in the cylinder, a closure for each end of the cylinder, means for admitting air to the upper end of the cylinder, means for exhausting air from the lower end of the cylinder to cause downward movement of the piston by atmospheric pressure, pads on each side of the piston to receive a sole and shoe, means carried by the cylinder in each end thereof to oppose pressure of the pad, and means operated automatically during rotation of the cylinder to admit air to the end of the cylinder which was down and to exhaust air from the end which was up.

13. Apparatus for cement-attaching soles to shoes comprising a cylinder open at both ends, trunnions on the cylinder at right angles to its longitudinal axis, supports for the trunnions to permit rotation of the cylinder to position either end up, a piston in the cylinder, sole-pressing pads on each side of the piston, means in each end of the cylinder to support a shoe against pressure of the pad, closures for each end of the cylinder, means for admitting air to whichever end of the cylinder may be up, and means for exhausting air from whichever end of the cylinder may be down to cause downward movement of the piston by atmospheric pressure, thereby pressing a pad upon the shoe in the lowermost end of the cylinder, the admission of air to the end of the cylinder which may be down being initiated during rotation of the cylinder to bring that end up.

14. Apparatus for cement-attaching soles to shoes comprising a cylinder arranged to rotate on a horizontal axis so that either end may be uppermost, a piston in the cylinder, a pad mounted on each side of the piston, abutments mounted

on the wall of the cylinder for holding a shoe against movement axially of the cylinder in each end portion thereof, means for forcing the abutments against the shoe to hold it in place upon the pad, said abutments having a limited yielding movement, an air-tight closure for each end of the cylinder, and means for withdrawing air from the lower end of the cylinder and supplying air to its upper end whereby atmospheric pressure causes the piston to move the pad toward the shoe supported by said abutments in the lowermost end of the cylinder, the piston movement taking up the yield in the abutments and applying pressure positively to the shoe.

15. Apparatus for cement-attaching soles to shoes comprising a cylinder mounted to revolve upon a horizontal axis so that either end may be disposed upwardly, a piston in the cylinder, a pad on each side of the piston, a shoe support on the cylinder wall in each end of the cylinder so arranged that movement of the piston will apply pressure to one shoe and relieve pressure on the other, closures for each end of the sleeve, and means for exhausting air from the lower end of the cylinder to cause pressure to be applied to the shoe in that end of the cylinder and to cause the other end of the cylinder to be opened to atmospheric pressure.

16. Apparatus for cement-attaching soles to shoes comprising a cylinder open at both ends, trunnions on the cylinder at right angles to its longitudinal axis, supports for the trunnions to permit rotation of the cylinder to position either end up, a piston in the cylinder, a closure for each end of the cylinder, means for admitting air to the upper end of the cylinder, means for exhausting air from the lower end of the cylinder to cause downward movement of the piston by atmospheric pressure, abutments for a shoe carried by the cylinder in each end thereof, and a sole-attaching pad on each side of the piston whereby downward movement of the piston will apply pressure to one shoe and relieve pressure upon the other shoe.

17. Apparatus for cement-attaching soles to shoes comprising a cylinder open at both ends, trunnions on the cylinder at right angles to its longitudinal axis, supports for the trunnions to

permit rotation of the cylinder to position either end up, a piston in the cylinder, a sole-pressing pad on each side of the piston, means in each end of the cylinder to support a shoe against pressure of the pad, closures for each end of the cylinder, means for admitting air to whichever end of the cylinder may be up, means for exhausting air from whichever end of the cylinder may be down to cause downward movement of the piston by atmospheric pressure, thereby pressing a pad upon the shoe in the lower end of the cylinder, and means for initiating the exhaustion of air from the upper end of the cylinder during its rotation to the lower position.

18. Apparatus for cement-attaching soles to shoes comprising a cylinder mounted for rotation about a horizontal axis, a piston in the cylinder, abutments for the shoe mounted on the cylinder wall in each end of the cylinder, a sole-pressing pad fixed to each side of the piston, said abutments and pad being so arranged that movement of the piston will move one of the pads toward the abutments to apply pressure to a shoe held thereby, a cover for closing each end of the cylinder, an air duct leading from each end of the cylinder to a valve, and an air pump connected to the valve, said ducts entering the cylinder at points which will be covered by the piston before excessive movement of the piston takes place in either direction, rotation of the cylinder on its axis operating said valve to connect one of the ducts with the air pump and the other with the atmosphere.
